United States Patent Office

Des. 176,323
Patented Dec. 13, 1955

176,323

LIPSTICK CONTAINER

Lurelle Guild, New York, N. Y., and Henrietta P. Manville, Woodbury, Conn., assignors to Revlon Products Corporation, New York, N. Y., a corporation of New York

Application January 27, 1955, Serial No. 34,249

Term of patent 7 years

(Cl. D86—10)

Fig. 1

Fig. 2

Fig. 3.

Fig. 4.

Fig. 1 is a view in elevation of a lipstick container showing our new design.

Fig. 2 is a view in elevation turned 180 degrees with respect to Fig. 1.

Fig. 3 is a view in elevation turned 45 degrees with respect to either Fig. 1 or Fig. 2.

Fig. 4 is a top end view thereof, the opposite end being identical to that shown.

We claim:

The ornamental design for a lipstick container, as shown and described.
